US00D784210S

(12) **United States Design Patent** (10) Patent No.: **US D784,210 S**
Marini et al. (45) Date of Patent: **** Apr. 18, 2017**

(54) **CHAIR BACK**

(71) Applicant: **HNI Technologies Inc.**, Muscatine, IA (US)

(72) Inventors: **Conrad M. Marini**, Woodbridge (CA); **Paul Mazzotta**, Etobicoke (CA)

(73) Assignee: **HNI Technologies Inc.**, Muscatine, IA (US)

(**) Term: **14 Years**

(21) Appl. No.: **29/515,992**

(22) Filed: **Jan. 28, 2015**

(51) LOC (10) Cl. **12-12**

(52) U.S. Cl.

USPC **D12/133**

(58) **Field of Classification Search**

USPC **D12/128-133**

CPC **A61G 5/00-5/14**

See application file for complete search history.

(57) **CLAIM**

The ornamental design for a chair back, as shown and described.

DESCRIPTION

FIG. 1 is a perspective view of the chair back from a first point of view.

FIG. 2 is a perspective view of the chair back from a second point of view.

FIG. 3 is a front view of the chair back.

FIG. 4 is a left side view of the chair back.

FIG. 5 is a back view of the chair back.

FIG. 6 is a right side view of the chair back.

FIG. 7 is a top view of the chair back; and,

FIG. 8 is a bottom view of the chair back.

The broken line showing is included for the purpose of illustrating unclaimed subject matter and forms no part of the claimed design.

1 Claim, 8 Drawing Sheets
